UNITED STATES PATENT OFFICE.

THOMAS DANQUARD, OF NEW YORK, N. Y., ASSIGNOR TO AUTOPIANO CO., OF NEW YORK, N. Y.,
A CORPORATION OF NEW YORK.

DOUBLE TRACKER MECHANISM.

No. 902,482.

Specification of Letters Patent.

Patented Oct. 27, 1903.

Application filed May 29, 1903. Serial No. 435,703.

To all whom it may concern:

Be it known that I, THOMAS DANQUARD, a citizen of the United States, residing at New York, in the county of New York and State of New York, have invented a new and useful Double Tracker Mechanism, of which the following is a specification.

This invention relates to a pneumatic musical instrument or player having a plurality of sets of tracker channels.

The principal objects of the invention are to provide improved means for controlling two or more sets of tracker channels, especially so that both eighty-eight and sixty-five note music sheets can be used on the same instrument, for operating a double tracker whereby only one of the sets of tracker channels will be exposed at the same time; to provide means for concealing the operating mechanism and all sets of tracker channels except one; and to provide simple means for operating the channel closing means from pneumatics in such a way that they are held away from the trackers in a substantially positive manner when the instrument is not in use, and are held yielding against the inoperative tracker when the other one is in use. These results are accomplished by means of improved constructions which also constitute parts of this invention.

Further objects and advantages of the invention will appear hereinafter.

Reference is to be had to the accompanying drawings which show certain forms in which the invention may be carried out, and in which,

Figure 1 is a front view of part of a tracker box and connected parts constructed in accordance with this invention. Fig. 2 is an end elevation thereof. Fig. 3 is a transverse sectional view through the center of Fig. 1. Fig. 4 is a view similar to Fig. 2 showing another form in which the invention may be carried out. Fig. 5 is a view similar to Fig. 2 showing a hand-operated construction coming under this invention, and Fig. 6 is a fragmentary elevation of a portion thereof.

The invention will first be described with special reference to Figs. 1, 2 and 3 in which is shown a tracker box 10 having the usual music sheet spools 11. It is shown as provided with an oscillating shaft 12 carrying a pair of end blocks 13 on which are supported a pair of trackers 14. These trackers are

independently and removably mounted on the end blocks, as for example by means of screws 15, so that each one can be taken off and repaired, cleaned or renewed without disturbing the other. The shaft 12 may be operated in any convenient manner as for example by means of an arm 16 extending therefrom, a link 17 and a hand lever 18 connected with the link.

Mounted in the tracker box, preferably on supports 20, is a cover or shield 21 which extends inwardly from both sides to the face of the tracker which happens to be in operative position and covers the remainder of the tracker mechanism. It may be considered as having a slot 22 therein which exposes substantially the entire face of one tracker, the other tracker always being concealed behind the shield. In order that the parts may operate conveniently in this way, the trackers may if desired be made of segmental shape.

Two sets of tracker channels 25 and 26 are shown connected with conduits 27 and 28, respectively. It will be understood that in accordance with the principal function of this invention, there will be 88 tracker channels and conduits in one series and 65 in the other, but these numbers may vary if required. All the conduits of the smaller set 29 connect with a series of primary pneumatics. A corresponding number of the other set connect with the same primary pneumatics and the excess ones with additional primary pneumatics of a similar character, (not shown). The conduits 27 and 28 preferably are made flexible so as to permit of the necessary motion of the tracker.

In order to close the set of conduits which is turned to inoperative position, a pair of caps 30 and 31 are shown. These caps are mounted on sheet metal plates 32. It has been found in practice that a leather cap sometimes sticks to the tracker, which is ordinarily of metal, if pressed against it, and that it discolors it badly. It is desirable therefore to remove the caps when the instrument is not in use and to keep them out of the way of the returning tracker so that there will be no danger of the tracker engaging the end of the cap and straining the plates 32. Accordingly means is provided whereby the caps 30 and 31 are kept positively back against the shield out of the path of the tracker when not in use. In the form shown

in the first three figures, this is accomplished by the following mechanism. On the shaft 12 is placed a disk or cam 35 having one or more notches 36 therein. Adjacent to these 5 are mounted a pair of pawls 37 mounted on rock shafts 38. The shafts 38 support the caps 30 and 31, through the plates 32 which are fixed to them and turn therewith. Consequently, when the disk 35 is turned so that 10 one of the pawls can enter the notch therein, the corresponding shaft 38 can be turned to cause its cap to press against the tracker. At the same time the other pawl is held out from the center of the disk or cam and its cap 15 therefore is prevented from moving into the empty space under it. In Figs. 2 and 3 the cap 30 is thus held back while the cap 31 is caused to close the channels 26. Springs 39 are employed to tend to lift the pawls from 20 the disk so as to hold both caps away from the trackers when the instrument is not in use and means is provided for overcoming these springs to pull the pawls into contact with the disks, and one of the caps on its 25 tracker, when the instrument is started. For this purpose the pawls are provided with links 40 which in this form of the invention are connected with pneumatics 41 and 42, which are connected with the wind inducing 30 devices (not shown) by a passage 43 or in any other convenient manner. For operating the rods 40 springs 44 are shown secured to the movable leaves of the pneumatics and extending beyond the ends thereof, so as to 35 hold the pawls 37 against the disk 35 and one of the caps against the tracker, with a yielding pressure when the instrument is being operated.

It will be seen that when the instrument 40 is idle and the two pneumatics are expanded, both caps are held away from the tracker by means of light springs 39 opposed by the springs 44. In order to positively hold them in this position blocks 440 are mounted on 45 the movable leaves of the pneumatics, and arranged to bear on the springs 44 when the pneumatics are expanded. These springs 44 press with a certain tension against the blocks 440 when the pneumatics are expanded, but as they collapse the springs follow the 50 blocks only so far as the pawls will allow, when they lift from the blocks while the pneumatics collapse entirely. This provides for holding the caps yieldingly on the trackers by means of springs 44. But only one cap can move inwardly the other one being held out by the contact of its pawl with the disk 35. It will be observed, of course that the disk or cam 35 oscillates with the trackers in this form of the invention as it is mounted on the shaft 12. In the form 60 shown in Fig. 4, a reciprocating bar 45 is substituted for the disk 35 and it is provided with a pair of notches 46 so located that only 65 one of the pawls 47 can enter its notch at the

same time, the other one being held out. These pawls are operated in the same manner as those which have been described and the bar 45 is connected with the operating link 17 by an arm 60, so as to move with the 70 trackers. As illustrated, the trackers are in their uppermost position and the upper pawl is allowed to sink into its notch, when the pneumatics 41 and 42 feel the suction, so as to cause the cap 30 to press against its 75 tracker while the lower pawl is held back. In that case the cap 31 is prevented from moving in toward the tracker.

In Figs. 5 and 6 the pawls are shown as being operated by hand instead of by pneumatic means. In this case a sliding bar 50 which may be moved up and down by a handle 51 carries two flat springs 52 which overbalance two light spiral springs 53 connected with the pawls 54. When the bar is 80 pushed upward the two pawls are released and when down the caps are pressed on the tracker. In this case a cam or disk 55 is employed similar to the disk 35, and the handle 51 must always be pushed down before the 85 handle 18 is moved to shift the tracker. Then after the trackers are set, the handle 51 must be pushed up again.

While I have illustrated and described certain forms in which the invention may be 90 embodied, I am aware that many modifications may be made therein by any person skilled in the art without departing from the scope of the invention as expressed in the claims. Therefore, I do not wish to be limited to the particular forms of the invention 95 shown, but

What I do claim is:—

1. In a tracker mechanism, the combination of a plurality of swinging blocks with a 100 plurality of tracker bars each removably mounted on said blocks.

2. In a tracker mechanism, the combination of two swinging end blocks with two 105 trackers supported at their ends on the end blocks and each independently removable therefrom, and means for turning the end blocks to move the trackers into and out of operative position.

3. In a tracker mechanism, the combination of oscillating supports, with a plurality of trackers removably mounted thereon, conduits connected with said trackers, primary pneumatics with which said conduits communicate, and movable caps adapted to 115 be turned against the trackers to close the conduits.

4. A tracker mechanism comprising a movable tracker having air channels, a cap adapted to close the channels, a spring for 120 normally holding said cap away from the tracker, and means connected with the action for moving the cap against the tracker when the tracker is in position adjacent thereto.

5. A tracker mechanism comprising mov- 125

- able tracker, a stationary shield projecting over said tracker, a cap, means for yieldingly holding said cap against the shield away from the tracker and means whereby said cap will be turned against the face of the tracker.
6. A swinging tracker having a curved front surface and two sets of tracker channels and provided with a stationary shield adapted to cover a part of said surface and having an opening therein of sufficient width to expose only one of the sets of tracker channels at a time.
7. The combination with a movable tracker having a plurality of sets of tracker channels, of a shield having an opening therein of sufficient width to expose only one of said sets of channels at a time.
8. The combination with a movable tracker having two sets of tracker channels, of a shield having an opening therein of sufficient width to expose only one of said sets of channels at a time, and means for closing the other set of channels.
9. The combination with a movable tracker having a plurality of sets of tracker channels, of a shield having an opening therein of sufficient width to expose only one of said sets of channels at a time, and means within said shield for closing each set of channels when it is moved within the shield.
10. The combination with a movable tracker having two sets of tracker channels, of a shield having an opening therein of sufficient width to expose only one of said sets of channels at a time, and yielding means adapted to be operated by air suction in said channels for closing either set of channels when located inside said shield.
11. The combination with a movable tracker having two sets of tracker channels, of a shield having an opening therein of sufficient width to expose only one of said sets of channels at a time, yielding means for closing either set of channels when located inside said shield, and means for preventing the yielding means from operating when the tracker is moved away from said yielding means.
12. The combination with a movable tracker having a plurality of sets of tracker channels, of a shield having an opening therein to expose said sets of channels, yielding means for closing either set of channels when located inside said shield, and means for preventing the yielding means from operating when the tracker is moved away from it, said means comprising a movable part having a notch therein, levers having pro-
- jections adapted to enter said notch, and means for operating said levers.
13. The combination with a movable tracker having two sets of tracker channels, of a shield having an opening therein to expose one of said sets of channels, means for closing either set of channels when located inside said shield, and means for preventing said means from operating when the tracker is moved away from it, comprising a movable part having a notch therein, levers having projections adapted to enter said notch, and pneumatics for operating said levers.
14. In a tracker mechanism, the combination of a double movable tracker, means for moving it to operative and inoperative position, a pair of caps for closing the inoperative part of the tracker, and means for holding one of said caps away from the path of the tracker.
15. The combination with a tracker having two sets of channels, of means for closing either set of channels, a part adapted to move with the tracker and having a notch therein, levers having projections adapted to enter said notch and connected with said closing means.
16. In a musical instrument, the combination with movable trackers, of caps for closing the channels thereof, yielding means for operating said caps, and pneumatics for operating the yielding means.
17. In a musical instrument, the combination with movable trackers, of caps for closing the channels thereof, yielding means for operating said caps, pneumatics for operating the yielding means, and means connected with each pneumatic for positively controlling the yielding means while the pneumatic is expanded and adapted to lose control thereof when the pneumatic is under suction.
18. In a tracker operating device, the combination of a pneumatic, a block on the movable leaf thereof having a projection, a spring connected with the movable leaf and adapted to be engaged by the end of the block when the pneumatic is expanded, and to be free thereof when the pneumatic is collapsed, and a rod connected with said spring controlling the cap of the tracker bar.
- In testimony whereof I have hereunto set my hand, in the presence of two subscribing witnesses.
